US00D757583S

(12) **United States Design Patent**
Roush et al.

(10) **Patent No.:** **US D757,583 S**
(45) **Date of Patent:** **** May 31, 2016**

(54) **FITNESS DEVICE**

(71) Applicant: **Garmin Switzerland GmbH**,
Schaffhausen (CH)

(72) Inventors: **Adam W. Roush**, Prairie Village, KS
(US); **Brian F. Ruff**, Olathe, KS (US);
Scott H. Wrenick, Merriam, KS (US)

(73) Assignee: **Garmin Switzerland GmbH** (CH)

(***) Term: **14 Years**

(21) Appl. No.: **29/493,626**

(22) Filed: **Jun. 11, 2014**

(51) LOC (10) Cl. **10-04**

(52) U.S. Cl.

USPC **D10/98**; D10/70; D24/167

(57) **CLAIM**

The ornamental design for a fitness device, as shown and described.

DESCRIPTION

FIG. 1 is a front perspective view of a fitness device showing our new design;

FIG. 2 is a rear perspective view of the fitness device;

FIG. 3 is a top view of the fitness device;

FIG. 4 is a front view of the fitness device;

FIG. 5 is a bottom view of the fitness device;

FIG. 6 is a rear view of the fitness device;

FIG. 7 is a left side view of the fitness device; and,

FIG. 8 is a right side view of the fitness device.

The broken lines shown in FIGS. 1 through 8 illustrate portions of the fitness device that form no part of the claimed design.

1 Claim, 4 Drawing Sheets
